U.S. Cl. D48—31

FIG. 1.

FIG. 2.

FIG. 3.

FIG. 4.

FIG. 1 is a perspective view of a vertically louvered, expanded metal topped lighting fixture of my new design; FIG. 2, a top plan view thereof;

FIG. 3, a front elevation view thereof; and,

FIG. 4, a side elevation view thereof, the opposite side and rear being identical thereto.

The characteristic features of my design reside in the vertical louvers in the front and in the expanded metal on the top.

I claim:

The ornamental design for a lighting fixture, substantially as shown and described.
